CLAIM

The ornamental design for a product package for absorbent articles, as shown and described.

DESCRIPTION

FIG. 1 is a perspective view of a fourth embodiment of a product package for absorbent articles;

FIG. 2 is a front view of the embodiment of the package shown in FIG. 1;

FIG. 3 is a left side view of the embodiment of the package shown in FIG. 1;

FIG. 4 is a rear view of the embodiment of the package shown in FIG. 1;

FIG. 5 is a right side view of the embodiment of the package shown in FIG. 1;

FIG. 6 is a bottom view of the embodiment of the package shown in FIG. 1; and,

FIG. 7 is a top view of the embodiment of the package shown in FIG. 1.

Broken lines are included for the purpose of illustrating environment and form no part of the claimed design.

1 Claim, 7 Drawing Sheets
